UNITED STATES PATENT OFFICE.

AUGUSTIN I. DAVIS, OF LOWELL, MASSACHUSETTS, ASSIGNOR TO AMERICAN MASON SAFETY TREAD COMPANY, OF SACO, MAINE, A CORPORATION OF MAINE.

SAFETY-TREAD FOR STAIRS AND STEPS.

973,346.

Specification of Letters Patent. Patented Oct. 18, 1910.

Application filed November 3, 1908. Serial No. 420,927.

To all whom it may concern:

Be it known that I, AUGUSTIN I. DAVIS, a citizen of the United States, residing at Lowell, in the county of Middlesex and 5 Commonwealth of Massachusetts, have invented a certain new and useful Improvement in Safety-Treads for Stairs and Steps, of which the following is a specification.

This invention relates to safety-treads for 10 stairs and steps and the object of said invention is to produce, especially for indoor use, a comparatively inexpensive safety-tread, in which an ornamental appearance is combined with non-slipping qualities.

15 I form the body of the base of sheet metal bent or folded to form one side of a groove for the reception of non-slipping material, the other side of said groove being formed by a nosing-piece which may be of more 20 durable or more ornamental material or which may combine both of these qualities. I have also shown the base provided with means for holding down the front edge of a mat which may be of any material com- 25 monly used for the purpose, as linoleum, rubber, cork-carpet or other suitable sheet material.

In the accompanying drawing, on two 30 sheets, Figure 1, is an isometric perspective view of a part of a stair provided with my improvement, the stair-tread and risers and the safety-tread being in vertical sections on lines at right angles to the front edge or nosing of a stair; Fig. 2, a vertical section 35 on the line 2 2 in Fig. 1; Fig. 3, a plan of a part of the base shown in Figs. 1 and 2; Fig. 4, an isometric perspective view of the base and filling, showing a modification of the groove; Fig. 5, a similar view of a mat 40 and a base with a modification of the nosing-piece and means of attaching the same to the base; Fig. 6, a similar view of another modification of the base and nosing-piece showing also the tread of a step and a mat; 45 Fig. 7, similar to Fig. 6, but omitting the mat and showing a modification of the nosing-piece.

A denotes a tread of a step or stair, and B, risers, all being of usual construction.

50 The safety-tread is represented in Figs. 1, 2 and 3 as having a sheet-metal base C, doubled upon itself at c c¹ and having these doubled portions or folds inclined away

from each other, the part or fold c receiving the front beveled edge of a mat D which 55 may be of linoleum, rubber, cork-carpet or other sheet material suitable for the purpose, and thick enough to reach to the top of the fold c, said mat being secured in place by any usual means, preferably by tacks driven 60 through said mat and through holes c² with which said base C is provided into the tread A. The base between the folds c c¹ is provided at intervals with holes c³ to receive screws E by which said base is secured to 65 the tread A of a step. The fold c¹ forms the back or inner side of a dovetail groove G for the reception of any non-slipping material as lead or other adhesive material or a suitable cement made non-slipping by containing grits or otherwise in any well known manner. The front side of said groove G is formed by a nosing-piece H which extends up to the same height as the folds c c¹, the lower part of said nosing-piece being secured 75 by solder, welding or equivalent means to the front part c⁴ of the base which is turned down over and fits the nosing a or front edge of the tread A. The nosing-piece is preferably secured to the nosing a by screws 80 E¹ which pass through holes c⁵ formed at suitable intervals in said nosing-piece.

In the remaining figures (4-7) showing modifications, the letters of reference previously mentioned, indicate parts which are 85 substantially like those above described. In Fig. 4, the upper half of the fold c⁶ farthest from the nosing is bent forward at c⁶ in such a manner that the lower part thereof serves to retain the front edge of the mat in place 90 while the upper part of said fold overhangs in a forward direction and retains the filling F in place, the fold c⁶ thus serving the purpose of the two folds c c¹ in Figs. 1-3. In Fig. 5, the front marginal part c⁷ of the base 95 is turned up instead of down and enters a fold h in the upper part of the nosing-piece H¹. In Figs. 6 and 7, the nosing H² H³ is represented as of thicker material, as of cast metal, and riveted at h¹ h² to the front or 100 nosing part c⁴ of the sheet metal base.

In all the forms of my invention the nosing is necessarily secured to the base before the anti-slipping material is applied and both of these operations will preferably 105 be done at the factory. The mat D is put

in place after the base is secured in position.

The tread, if worn, will be leveled in the usual manner as by means of cement I laid 5 in the depressions α^1 . (See Figs. 1 and 2.)

I claim as my invention:—

1. The combination of a sheet-metal base having an upwardly extending fold and a nosing secured to said base and extending 10 downward in front of the tread of a step or stair and upward as high as the top of said fold, to form with said fold and the intervening portion of said base a continuous dovetail groove for the reception of anti- 15 slipping material.

2. The combination of a sheet-metal base having an upwardly extending fold and a nosing-piece of different material secured thereto and arranged and adapted to form 20 with said fold and the intervening portion

of the base, a continuous dovetail groove for the reception of non-slipping material.

3. The combination of a sheet-metal base having an upwardly extending fold, a nosing secured to said base and extending upward as high as the top of said fold, to form with said fold and the intervening portion of said base, a continuous dovetail groove for the reception of anti-slipping material and a mat arranged on said base, said base 30 being provided with holes through which tacks may be driven to secure said mat in place.

In witness, whereof, I have affixed my signature, in presence of two witnesses.

AUGUSTIN I. DAVIS.
